UNITED STATES PATENT OFFICE.

J. RAYMOND PLANK, OF GRAND RAPIDS, MICHIGAN.

UNIVERSAL JOINT.

1,147,887.

Specification of Letters Patent. Patented July 27, 1915.

Application filed February 17, 1914. Serial No. 819,183.

To all whom it may concern:

Be it known that I, J. RAYMOND PLANK, a citizen of the United States of America, residing at Grand Rapids, in the county of Kent and State of Michigan, have invented certain new and useful Improvements in Universal Joints; and I do hereby declare the following to be a full, clear, and exact description of the invention, such as will enable others skilled in the art to which it appertains to make and use the same.

This invention relates to improvements in universal joints, and its object is to provide a device of this character which will be simple and strong in construction, easily assembled or disassembled without any use of tools; to provide simple and effective means for lubrication, and to provide the device with various novel features of construction and arrangement as hereinafter more fully described and particularly pointed out in the claims.

The invention consists essentially of two similar jaws each having an arc-shaped groove the axis of which lies in a plane at right angles to the axis of rotation of the jaw and of more than one hundred and eighty degrees in length, whereby the open ends of the grooves are spaced apart less than twice the radius of the grooves, and a center or connecting member having arc-shaped ribs in planes at right angles to each other to fit slidably in said grooves, said ribs being more than a half circle in length and each rib being adapted to readily enter a groove when inserted one end first and retained by the jaw when in working position therein.

It further consists of means for effectually lubricating the device when in operation.

A preferred embodiment of the invention is illustrated in the accompanying drawings, in which:—

Figure 1 is an elevation of the device; Fig. 2 is an axial section of the same, showing the jaws angularly arranged; Fig. 3 is a perspective view of one of the jaws; and Fig. 4 is a perspective view of the center block.

Like numbers refer to like parts in all of the figures.

The center block 1 is an integral member consisting of substantially two intersecting disks arranged in planes at right angles and preferably having a common center. Each

disk is reduced at one side leaving the greater portion thereof, the margin of which forms an arc-shaped rib of more than a semicircle and of substantially the same dimensions as the groove in a jaw, and adapted to enter and slidably fit within the same. The jaws 2 are duplicates except that one is preferably provided with a round socket 3 having a keyway and adapted to receive a shaft, while the opposite jaw is provided with a squared socket 4 to slidably receive the end of another shaft. Each jaw is provided with an arc-shaped groove 5 greater than a semi-circle which groove receives one arc-shaped margin or rib of the center block, and the said jaw is assembled upon the block by turning the same to such an angle relative to the same that one end of the rib will first enter the groove and the converging tips of the jaws will pass the narrowed width of the ribs of said disk. The jaw is then turned approximately in line with the axis of rotation and will be retained upon the block by the converging tips of the jaws which extend beyond the greatest diameter of the disk. The proportions of the different parts are such that the jaws will be retained upon the center block in any angle out of alinement that it is practicable to operate the joint, it being necessary to turn the jaws out of alinement to a considerable angle before they can be attached to or detached from the center block. The arc of the jaws and ribs should be as great as possible and permit the assembly of the parts as described.

An oil chamber 7 is provided in the bottom of the groove 5 of each jaw, and these chambers also extend into the grooves opposite the bearing surfaces of the center block 1, and these bearing surfaces are provided with arc-shaped oil grooves 8, those on opposite sides of each disk being joined by holes 9 through the disk, said holes being preferably diametrically opposite. The jaws 2 are long enough so that when the device is in operation the said holes and oil grooves will never be uncovered by the jaws.

The oil chambers 7 may be filled with either a hard grease or porous material, such as wicking, soaked in oil, and when the device is in operation the lubricant will be transmitted to the grooves 8 and will flow by centrifugal force to the greatest diameter of the grooves in the jaws and be retained within the grooves. As the tips

of the jaws project beyond the greatest diameter and converge, an oil pocket is thus formed, which prevents the lubricant being thrown from the joint by centrifugal force.

5 Any inequality of lubricant upon opposite sides of the disk will be equalized by means of the holes 9, which permit the lubricant to flow from one side of the disk to the other.

From the foregoing, the operation and 10 advantages of the device are obvious without further description.

What I claim is:—

1. A universal joint, comprising a center block having two arc shaped ribs arranged 15 in planes at right angles to each other, each rib being more than a semi-circle in length, and two jaws each having an arc-shaped groove greater than a semi-circle to receive one of the respective ribs.

20 2. A universal joint, comprising a center block having two intersecting arc shaped ribs of more than 180 degrees long, and arranged in planes at right angles to each other, two jaws each of which has an arc-shaped groove of more than 180 degrees to receive the margin of the respective disk and means in said jaws for supplying lubricant to the bearing surfaces of the jaws and center block.

30 3. A universal joint, comprising a center block having two arc shaped ribs of more than semi-circular length arranged in planes at right angles to each other, and two jaws each having an arc-shaped groove greater than a semi-circle to receive the respective rib and also having an oil chamber communicating with said groove.

40 4. A universal joint, comprising a center block provided with two arc shaped ribs of more than semi-circular length arranged in

planes at right angles to each other, and two jaws each having an arc-shaped groove greater than a semi-circle to receive the respective disk and also an oil chamber communicating with said groove, the bearing 45 surfaces of the center block being provided with oil grooves on opposite sides and joined by passages therethrough.

5. A universal joint, comprising a center block having two arc-shaped ribs of more than semi-circular form arranged in planes at right angles to each other, and having a common center, two jaws each having an arc-shaped groove greater than a semi-circle 50 to receive the respective disk and also having an oil chamber communicating with said groove, the bearing surfaces of the center block also having oil grooves and 55 passages to connect the opposing grooves in the disks.

6. In a universal joint, jaws each adapted to be attached to a shaft, each jaw having an arc shaped groove of more than a half circle in length, the axis of which groove is perpendicular to the axis of rotation of the 65 jaw, and a connecting member having arc shaped ribs at right angles to each other and slideable one in each groove, each of said ribs being of such angular extension that it is readily inserted into its respective groove 70 when in one relative position and securely retained therein in any regular operative position of the parts.

In testimony whereof I affix my signature in presence of two witnesses.

J. RAYMOND PLANK.
